UNITED STATES PATENT OFFICE

CHARLES B. ULRICH, OF JAMESTOWN, NEW YORK, ASSIGNOR TO ART METAL CONSTRUCTION COMPANY, OF JAMESTOWN, NEW YORK, A CORPORATION OF MASSACHUSETTS

DESK

Application filed February 15, 1932. Serial No. 592,859.

My invention pertains to an improved construction of desk adapted for use particularly in large offices where many desks must be placed close together, for example in rows, 5 or back to back, or both, the purpose of my improved desk construction being to provide a more sanitary construction of desk for cleaning purposes generally, and at the same time to materially cheapen the cost of the 10 desk without impairing its quality or utility in any way.

In connection with the use of desks for business purposes generally, greater cleanliness and better sanitation have resulted in the 15 so called sanitary desk coming into practically universal use. This type of desk is provided with legs of substantial length extending below the bottom portions of the desk enclosures, which permits the floor to 20 be kept clean under the desk. This construction of desk generally consists of two pedestal sections one at either end of the desk, to which the top of the desk is secured to make a rigid structure, the desk structure under the 25 desk top and between the pedestals, if any, having practically nothing to do with the strength and rigidity of the desk. In view of the pedestals constituting the real framework of the desk, and also constituting the supports for the desk, it has heretofore been 30 considered that each pedestal should individually have stable support, to impart stable support to the desk as a whole. To effect this stability of support, each pedestal has heretofore been provided with four legs, one at 35 each of its corners, so that each pedestal serves as a column to impart stable support to the top of the desk. While this construction is satisfactory where desks are used singly, it 40 is relatively expensive. Where it is required to use many of the desks close together, for example, end to end and back to back in large offices, as will appear below, many areas are produced on the floor under the desks, due to 45 the closeness of the end legs to adjacent end legs of other desks, which cannot be readily cleaned, and thus the very purpose of a sanitary desk construction is defeated. By my invention, I provide each of the desk pedestals 50 with but two legs, mounted in such position

under the pedestal, that the weight of the pedestal, or if preferred, the weight of the desk portion supported by the two legs, is substantially balanced upon said two legs, when the pedestal is in vertical position resting on 55 its legs. With my improved construction, when two of the pedestals are connected with a desk top, the structure as a whole is quite as effectively supported and quite as rigid as has been the case heretofore with twice the 60 number of legs per pedestal, the structure is materially cheaper to make, and it at the same 65 time has the marked advantage where the desks are used close together in large offices, of materially spacing the legs of any desk pedestal, from the legs of an adjacent pedestal of 70 the next desk, even though the desk tops be so close together that they touch each other. As a result, the floor under closely grouped 75 desks can be kept clean readily, and moreover 80 the work of cleaning the floor is much simplified on account of there being only half as many obstructions around which the cleaning 85 implement must be moved, as is the case where desks are used having four legs per 90 pedestal, and furthermore, ordinary cleaning 95 implements may be effectively employed and the slow operation of cleaning narrow spaces with special implements is avoided.

My invention will best be understood by 80 reference to the accompanying drawings 85 illustrating a preferred embodiment thereof, in which

Fig. 1 illustrates a row of desks in accordance with my invention, in front elevation.

Fig. 2 shows in a view similar to Fig. 1. 90 a row of desks of a construction commonly used heretofore.

Fig. 3 is a bottom view to an enlarged 95 scale, of a desk in accordance with my invention.

Fig. 4 shows in a view similar to Fig. 3. 100 one of the desks illustrated in Fig. 2.

Fig. 5 shows in plan view four pedestal desks having four legs per pedestal, closely 95 grouped end to end and back to back, to illustrate the small spaces between the legs of any desk and adjacent legs of adjoining desks,

Fig. 6 shows in a view similar to Fig. 5,

four desks having four corner legs each, closely grouped end to end and back to back, and illustrates the small spaces between the legs of any desk and adjacent legs of the adjoining desks, and

5 Fig. 7 shows in a view similar to Fig. 5, four pedestal desks provided with my improved leg construction, closely grouped end to end and back to back, to illustrate the large amount of space between any leg of any desk 10 and adjacent legs of the adjoining desks.

10 Similar numerals refer to similar parts throughout the several views.

As shown in Fig. 3, my improved desk construction consists of two pedestals 10 and 11

15 secured to a desk top 12, the pedestal 10 being provided with two legs 13, 13 and the pedestal 11 being similarly provided with two legs 14, 14. Each of the legs 13 is secured at its upper end to a member 15 extending across the bottom end of the frame of the pedestal 10, lengthwise of the desk, which is rigidly secured at its ends to the frame of the pedestal. Each of the legs 14 is similarly supported by a member 16 secured to the

20 lower portion of the frame of the pedestal 11. My improved construction may be applied to desks of any material, and where the desks are of wood, the members 15 and 16 may be secured in place by suitable fastening devices for example screws, and where the desks are of sheet metal, the members 15 and 16 are preferably metal members secured in place either by screws or bolts or other suitable fastening means, for example,

25 by spot welding. The legs of each pedestal are mounted preferably in a vertical plane extending from front to rear centrally through the pedestal, so that the weight of the pedestal and of the desk parts supported thereby, is substantially balanced on the legs of the pedestal, and that there is a substantial overhang of the pedestal on each side of said plane. Each of the front legs is preferably set back from the front bottom edge

30 of its pedestal, a substantial distance to prevent interference with the feet of the user, and to prevent interference with articles on the floor near the desk, and to afford a clearance around the desk, making it possible, for example, to accommodate small waste paper baskets, or other desk accessories, between and under the desks. Each of the rear legs is preferably similarly set in substantially

35 the same distance from the rear bottom edge of its pedestal, for a similar purpose, giving the structure a symmetrical appearance. As a result of this construction, when the pedestals 10 and 11 are secured to the desk top

40 12, they are rigidly maintained in vertical position by said top, and the legs are therefore rigidly held in vertical position to support the weight of the pedestals and of the other desk parts carried by the pedestals.

45 In this manner, although the desk is pro-

vided with only four legs, the weight of the desk is distributed on and supported by the legs, quite as effectively as is the case where each pedestal is provided with four legs. Furthermore, in cases requiring the use of

50 a large number of desks, for example in large offices, where the desks are arranged end to end as illustrated in Fig. 1, or end to end and back to back as illustrated in Fig. 7, it will be observed that a substantial clearance space

55 is provided between the legs 14 of each desk and the legs 13 of an adjacent desk, which permits the ready insertion between the legs of the adjacent desks, of any usual cleaning implement, in cleaning the floor under the

60 desks. It will also be observed that as a result of there being but four legs per desk, the number of obstructions in the path of any cleaning implement used, is but half what it is where four legs per pedestal are employed,

65 which is a considerable advantage in connection with cleaning the floor under the desks, where a large number of desks is used.

70 As illustrated in Fig. 4, for a sanitary pedestal desk of a kind commonly used heretofore, the desk consists of pedestals 20 and 21

75 secured to a desk top 22, the pedestal 20 being provided with four legs 23 which are the corner posts of the frame of the pedestal 20, the pedestal 21 being similarly provided with four legs 24, so that each pedestal has stable support, and serves effectively as a column supporting the desk top 22, but no more so

80 than do the pedestals of my improved construction. When a large number of desks of the construction in Fig. 4 are used together, for example end to end as illustrated in Fig.

85 2, or end to end and back to back as illustrated in Fig. 5, the end legs 24 of each pedestal are closely adjacent the end legs 23 of an adjacent

90 desk, the amount of clearance space between these end legs being so small as to prevent the insertion of floor cleaning implements between them, for example mops or floor

95 brushes of the kind ordinarily employed in cleaning large floors. This leaves many uncleaned and unsanitary areas on the floor, unless special cleaning means involving much additional work, are employed, all of which

100 is avoided by my improved construction.

105 In Fig. 6, I illustrate in plan view, four

110 desks 32, 32 placed end to end and back to back, each of said desks having two corner legs 33, 33 at one end and two corner legs 34, 34 at its other end. This view shows the

115 small amount of separation between any leg 33 and an adjacent leg 34 of any adjoining desk.

120 While the disadvantages above described resulting from using desks of previous constructions in single rows, end to end, as illustrated in Fig. 2, are serious, when such desks are used in double rows, end to end and back to back, as illustrated in Figs. 5 and 6, as

125

the disadvantages pointed out are much more serious; for, with the arrangement illustrated in either Fig. 5 or Fig. 6, it will be observed that under the four adjacent corners of each group of four desks, there is a small area or space practically surrounded by the adjacent corner legs of the four desks, which space can only be cleaned by reaching between two of said adjacent and closely spaced corner legs, and, furthermore, to effect any cleaning whatever of said space, it is necessary to reach under one of the desks and the entire distance from front to rear of the desk, before the said space is reached, making thorough cleaning of said space practically impossible. When it is realized that Figs. 5 and 6 are illustrative of small portions of long double rows of desks which are frequently used in the arrangement referred to, and that such an enclosed small space is produced for each four adjoining desks, the difficulty of maintaining sanitary conditions will be appreciated. With desks of the kind illustrated in Figs. 5 and 6, I find that the separation of adjacent legs of adjoining desks, represented by the dimension d , is frequently no more than from one to two inches; with my invention, on the other hand, the separation of adjacent legs of adjoining desks, represented by the dimension D in Fig. 7, may be much greater, for example, from fourteen to eighteen inches, depending on the size of the desk. This affords ample room to thoroughly clean under desks involving my invention, when they are closely grouped as described.

From the above, it will appear that by my invention I provide an improved sanitary desk structure quite as effective in every way as sanitary desk structures heretofore used, and with considerable reduction in cost of the desks and marked advantages in cleaning the floor under the desks, as well as increased useful floor space under the desks, where the desks are used closely together.

While I have shown my invention in the particular embodiment above described, it will be understood that I do not limit myself to this exact construction as I may employ equivalents known to the art at the time of the filing of this application without departing from the scope of the appended claims.

What I claim is:

1. In a sanitary desk construction adapting said desks for use end to end and back to back closely together in rows, a desk top, a pedestal secured to each end portion of said top, two legs supporting each pedestal a substantial distance from a floor for cleaning purposes under said pedestal, and a cross member secured to the bottom portion of each of said pedestals for each of its legs and extending longitudinally of the desk, each of said legs being secured to the mid-portion of one of said cross members, and said cross members for each of said pedestals being

spaced substantial distances inwardly from the bottom front and rear edges of said pedestal, whereby when a plurality of said desks are placed end to end or back to back or both, substantial clearance spaces are provided between all adjacent legs of different ones of said desks for cleaning purposes under the corresponding pedestals.

2. In a sanitary desk construction adapting said desks for use end to end and back to back closely together in rows, a desk top, a pedestal secured to each end portion of said top, two legs supporting each pedestal a substantial distance from a floor for cleaning purposes under said pedestal, and a cross member secured to the bottom portion of each of said pedestals for each of its legs and extending longitudinally of the desk, each of said legs being secured to the mid-portion of one of said cross members, whereby when a plurality of said desks are placed closely together in a row, substantial clearance spaces are provided between adjacent legs of different ones of said desks for cleaning purposes under the corresponding pedestals.

3. In a sanitary desk construction adapting said desks for use end to end and back to back closely together in rows, a desk top, a pedestal secured to each end portion of said top, two legs supporting each pedestal a substantial distance from a floor for cleaning purposes under said pedestal, and members secured to the bottom portions of said pedestals to support said legs, each of said legs being secured to one of said members under the mid-portion of the corresponding pedestal longitudinally of the desk, whereby when a plurality of said desks are placed closely together in a row, substantial clearance spaces are provided between adjacent legs of different ones of said desks for cleaning purposes under the corresponding pedestals.

4. In a sanitary desk construction adapting said desks for use end to end and back to back closely together in rows, a desk top, a pedestal secured to each end portion of said top, two legs supporting each pedestal a substantial distance from a floor for cleaning purposes under said pedestal, and members secured to the bottom portions of said pedestals to support said legs, each of said legs being secured to one of said members under the mid-portion of the corresponding pedestal longitudinally of the desk, whereby when a plurality of said desks are placed closely together in a row, substantial clearance spaces are provided between adjacent legs of different ones of said desks for cleaning purposes under the corresponding pedestals, said front and back legs being spaced substantial distances inwardly from the bottom front and rear edges respectively of the pedestals to which they are secured.

5. In a sanitary desk construction adapt-

ing said desks for use end to end and back to back closely together in rows, a desk top, a pedestal secured to each end portion of said top, and two legs supporting each pedestal a substantial distance from a floor for cleaning purposes under said pedestal and secured to said pedestal substantial distances from its outer vertical end wall, whereby when a plurality of said desks are placed closely together in a row, substantial clearance spaces are provided between adjacent legs of different ones of said desks for cleaning purposes under the corresponding pedestals.

6. In a sanitary desk construction adapting said desks for use end to end and back to back closely together in rows, a desk top, a pedestal secured to each end portion of said top, and two legs supporting each pedestal a substantial distance from a floor for cleaning purposes under said pedestal and secured to said pedestal substantial distances from its outer vertical end wall, said front and back legs being spaced substantial distances inwardly from the bottom front 25 and rear edges respectively of the pedestals to which they are secured, whereby when a plurality of said desks are placed end to end or back to back or both, substantial clearance spaces are provided between all adjacent legs 30 of different ones of said desks for cleaning purposes under the corresponding pedestals.

7. In a sanitary desk construction, the combination of a desk top, a pedestal secured to and supporting one end of said desk top, a support for the other end of said desk top, and two legs secured to and supporting said pedestal, said legs being substantially midway between the outer and inner end walls of said pedestal and spaced inwardly 40 substantial distances from the bottom front and rear edges of said pedestal.

8. In a sanitary desk construction, the combination of a desk top, a pedestal secured to and supporting each end of said desk top, 45 and two legs secured to and supporting each of said pedestals, said legs of each pedestal being substantially mid-way between the outer and inner end walls of the corresponding pedestal and spaced inwardly substantial distances from the bottom front and rear edges of the corresponding pedestal.

In witness whereof, I hereunto subscribe my name this 6th day of February, A. D. 1932.
